APERIODIC TRANSFORMER

Andrew Alford, San Mateo, Calif., assignor to
 Mackay Radio & Telegraph Company, New
 York, N. Y., a corporation of Delaware

Application December 28, 1937, Serial No. 182,092

6 Claims. (Cl. 178—44)

The present invention relates to high frequency transformers and especially to that type of transformer which consists essentially of a transmission line having variable characteristics along its length.

It is an object of my invention to provide a high frequency aperiodic transformer which shall be of convenient dimensions and of unusually simple construction. Particularly it is an object to provide a transformer of simple construction which is capable of transforming, without substantial reflection, waves whose wavelength is more than twice as long as the overall length of the transformer itself, even when the transformation ratio is as great as 1.2 to 1.

Another object of my invention is to provide such a transformer which is adapted to be constructed with the same materials and according to the same general principles of construction as are employed in erecting ordinary open-wire transmission lines. In accordance with my invention, an aperiodic transformer of conveniently small dimensions may be constructed with the same materials as are ordinarily employed in erecting open-wire transmission lines, and the construction may be performed by the same construction gangs who are employed for erecting antennae and transmission lines in the field and who are primarily skilled in the art of antenna and line construction.

One particularly useful feature of my invention is the arrangement whereby a desired curve of wire spacing may be very simply attained by the determination of only a very few dimensions, the construction being such that all the other spacing dimensions inherently assume the correct values when these very few dimensions are properly determined. In accordance with my invention, a transformer can readily be erected whose spacing distances are so accurately determined at all points that the transformer can, with substantially no reflection, transmit waves whose wavelength is four or more times the total length of the transformer, even when the transformer wire spacing at the high impedance end is several times as great as at the low impedance end.

Transformers of the "tapered transmission line" type have previously been suggested, in which discontinuously loaded telephone lines were proportioned by varying the magnitude or spacing of the loading coils so as to obtain a desired result. Such transformers, however, have not been well adapted for use with high frequencies nor with unloaded, open-wire lines. High frequency transformers have also been suggested in which the line spacings of an open-wire transmission line were varied along the length of the line, but the spacings of these transformers have been varied either in accordance with a straight taper or in accordance with some

other incorrect curve, so that these transformers have not been capable of usefully transforming, with substantially no reflection, waves whose wavelength was three or more times the length of the transformer itself.

In accordance with the present invention, a high frequency aperiodic transformer is constructed in the form of an open-wire transmission line without loading coils, so that the velocity of propagation of waves along this transformer remains substantially constant and substantially equal to the speed of light, and the surge impedance of this transformer is varied from point to point along the length of the transformer by merely varying the spacing between the two wires of the transformer in accordance with the formula

$$s = re^{(M-PN)-2} \quad (1)$$

where s is the center-to-center spacing of the two wires at any plane of measurement; r is the radius of each of the wires; P is the distance of the plane of measurement from the low impedance end of the transformer, expressed as a fraction of the total transformer length; e is the base of natural logarithms; M and N are parameters determined by the terminal spacings at the ends of the transformer.

By constructing a transformer in this manner it is unnecessary to vary the shape or size of the wires composing the transformer, and it is also unnecessary to connect inductances or capacitances in series or shunt with the line wire. The only dimension which must be varied along the length of the transformer is the spacing between the two wires which constitute the conductors of the transformer. It has been found experimentally that a transformer whose spacing varies in accordance with Formula (1) above set forth and whose wire diameter is constant is capable of transmitting, between lines whose surge impedances have a ratio of 14:10 or 13:10, and with substantially no reflection, waves whose wavelength varies between the shortest length available for measurement and a length which is three or four times as great as the overall length of the transformer itself.

In order to space the transformer conductors in accordance with Formula (1) it is possible to employ a large number of spreaders whose lengths and positions along the transformer are computed in accordance with the formula. In accordance with a further feature of the present invention, however, the spacing between conductors may be made to vary according to a curve closely approximating the curve defined by Formula (1) merely by stretching the two conductors as straight lines between a pair of low impedance terminals spaced apart a distance d and a pair of high impedance terminals spaced

apart a distance D . In order that such an arrangement may produce a curve of wire spacing which approximates the desired curve, the axis of the low impedance terminals should not lie 5 in the same plane as the axis of the high impedance terminals, but should be inclined at an angle ϕ with respect thereto. Assuming that the axis of the high impedance terminals is inclined at the angle ϕ with respect to the axis of the low impedance terminals, and that the distance between the high impedance terminals is D and the distance between the low impedance terminals is d , the spacing s between the two wires in any given plane of measurement perpendicular to the axis 10 of the transformer is given by the following general formula:

$$s = \sqrt{(P)^2 D^2 + 2(P)(1-P)Dd \cos \phi + (1-P)^2 d^2} \quad (2)$$

where P is the distance of the plane of measurement from the low impedance end of the transformer, expressed as a fraction of the total length of the transformer. When the angle ϕ is taken to be 90° the above Formula 2 may be expressed as follows:

$$s = \sqrt{P^2 D^2 + d^2 - 2Pd^2 + P^2 d^2} \quad (3)$$

Because of the greater convenience of running all transmission lines either in a horizontal or a vertical plane, it will be assumed that the high 30 impedance and low impedance terminals of the transformer are always at right angles, so that Formula (3) may be used instead of Formula (2) in all those cases where the transformer conductors are stretched as straight lines between the high impedance and low impedance terminals.

The preferred construction of the present invention may best be understood by reference to the accompanying drawings, in which

Fig. 1 is a perspective view of the simplest form 40 of transformer in accordance with my invention, connected between a transmission line which extends from a receiving antenna and a building which houses a receiving equipment;

Fig. 2 is a side elevation of the transformer 45 shown in Fig. 1;

Fig. 3 is a plan projection of the transformer shown in Fig. 2 as viewed in the direction of the arrows 3, 3 of Fig. 2;

Fig. 4 is an end elevation of the transformer 50 shown in Fig. 2 as viewed in the direction of the arrows 4, 4 of Fig. 2;

Fig. 5 is a side elevation of a preferred form of transformer in accordance with my invention;

Fig. 6 is a plan projection of the transformer 55 shown in Fig. 5 as viewed in the direction of the arrows 6, 6 of Fig. 5;

Fig. 7 is an end elevation of the transformer shown in Fig. 5 as viewed in the direction of the 60 arrows 7, 7 of Fig. 5;

Fig. 8 is an enlarged schematic representation of the conductor portions of the transformer shown in Fig. 7;

Fig. 9 is an inclined projection of the transformer shown in Fig. 7 as viewed in the direction of the arrows 9, 9, of Fig. 7;

Fig. 10 is a graphical representation of the spacing between conductors at different points along the length of two transformers of different dimensions constructed according to Figs. 1, 2, 3 and 4.

Referring now more particularly to Fig. 1, 101 is a building in which is housed a radio receiving equipment (not shown). Through the 75 wall of this building extend two lead-in insu-

lators 103 and 104. A cross arm 105 mounted on a pole (not shown) carries two petticoat insulators 106 and 107. Stretched between the lead-in insulators 103 and 104 and the petticoat insulators 106 and 107 are the two transformer conductors 120 and 130 which essentially constitute the transformer of my invention. The petticoat insulators 106 and 107 are disposed horizontally and spaced so that at the end points 121 and 131 the conductors 120 and 130 are spaced twelve inches apart center-to-center. The lead-in insulators 103 and 104, on the other hand, are vertically disposed and spaced so that at the end points 122 and 133 conductors 120 and 130 are spaced four inches apart center-to-center. Because of the angular relation between the end points 121—131 and the end points 122—132, the spacing between conductors 120 and 130 does not vary linearly from one end of the transformer to the other, but varies in accordance with the curve defined by Equation (3) set forth above. This curve of spacing will have the general form of the curves shown in Fig. 10, which represent the spacings for transformers of similar construction in which the high impedance spacings are respectively six and two times the low impedance spacing instead of being three times the low impedance spacing as in the transformer of Fig. 1.

Although the curve of variation of conductor spacing of the transformer shown in Fig. 1, as well as of the other two transformers represented by the curve of Fig. 10, is not theoretically identical with the curve of conductor spacing defined by Formula (1) set forth above, it has been found empirically that these curves approximately agree. More precisely, it has been found that the curve of conductor spacing of a transformer such as represented in Figs. 1 and 10, agrees with the curve of conductor spacing which would be obtained if two transformers, each designed in accordance with Formula (1), were connected end-to-end, one of these two transformers being a step-down transformer and the other one a step-up transformer of smaller ratio. Thus a transformer designed as shown in Fig. 1, or as represented in either of the curves of Fig. 10, is capable of transforming without appreciable reflection waves whose wavelength is several times the overall length of the transformer itself.

Experimental tests have also confirmed the fact 50 that a transformer designed in accordance with Fig. 1 or Fig. 10, provides an efficient, substantially reflection-free arrangement for stepping-up or stepping-down voltage, or current, or impedance over a frequency range whose upper limit 55 is practically unlimited and whose lower limit corresponds to a wavelength between two and four times the length of the transformer itself for transformation ratios of the approximate order required in practice.

Figs. 2, 3 and 4 represent orthographic projections from different directions of the transformer shown in Fig. 1. As can be seen most clearly from Fig. 3, the vertical disposition of the transformer conductors at the point where they enter the receiver building permits the transformer to be brought up to the building at any convenient angle, without introducing an objectionable difference in length in the two line conductors. For this reason it is ordinarily preferred to arrange 70 the terminals 122 and 132 in a vertical plane as shown, and to arrange the terminals 121 and 131 in a horizontal plane. Furthermore, the arrangement of terminals 121 and 131 in a horizontal plane is particularly convenient when the trans- 75

mission line to which the transformer is connected, is supported in the ordinary way upon horizontal cross arms which carry a plurality of petticoat insulators, such as 106 and 107.

Referring now more particularly to Figs. 5, 6, 7, 8 and 9, these figures represent a preferred form of transformer in accordance with my invention. This form of transformer is almost as simple to construct as the form illustrated in Figs. 1, 2, 3 and 4, and has the advantage that the curve of conductor spacing along the length of the transformer is even more closely like the ideal curve defined in Formula (1) than the spacing curve of the simpler form of transformer. As shown in Figs. 5, 6, 7, 8 and 9, this preferred form of transformer is essentially similar to the form illustrated in Figs. 1-4, but further comprises one intermediate insulating spacer 150 located intermediate the ends of the transformer, at a distance A from the low impedance end and at a distance B from the high impedance end of the transformer. This insulating spacer 150 serves as a spreader to keep the wires apart and is of length E which is less than length D but greater than length d. The length E of the spreader 150 is greater than the spacing between conductors 120 and 130 would be if the spreader were not provided. The distance A of the spreader from the low impedance end of the transformer is of the order of one-third of the total transformer length, this distance A being ordinarily between one-sixth and one-half of the total transformer length. The length E of the spreader is preferably substantially equal to the ideal conductor spacing at a plane A units from the low impedance end of the transformer, as determined from the theoretical Formula (1) set forth above.

In computing the conductor spacing at various points along the length of a transformer such as shown in Figs. 5, 6, 7, 8 and 9, the transformer may be considered as two simple transformers of the type illustrated in Fig. 1, these two transformers being connected together end-to-end. Of these two transformers the low impedance one may be considered as having a length A, a low impedance terminal spacing d, and a high impedance terminal spacing E. The higher impedance one of the two transformers may be considered as having a length B, a low impedance terminal spacing E, and a high impedance terminal spacing D. Although the overall angle between the axes of terminals 121 and 131 and terminals 122 and 132 is still 90° in this form of transformer, the individual angles of the two component transformers will no longer be 90°. For the low impedance one of the two component transformers, the angle ϕ may be considered to be equal to θ as shown in Fig. 8; while for the high impedance one of the two component transformers, the angle ϕ may be considered to be $90^\circ - \theta$. The angle θ will depend upon the distances A and B which define the position of the spreader 150. The angle θ may be computed from the following formula:

$$\frac{d \cos \theta}{A} = \frac{D \sin \theta}{B} \quad (4)$$

This formula will be understood by inspection of Figs. 9 and 7 or 9 and 8, Fig. 8 being merely an enlarged representation of the conductor portions of Fig. 7 with the supporting structure removed and with dimensions added. The above Formula (4) is derived upon the assumption that the fundamental angle ϕ between the terminals 121 and 131 and the terminals 122 and 132 is 90° for

the complete transformer. It is clear that if this angle ϕ were different from 90° the expression $\sin \theta$ in Formula (4) would have to be replaced by the expression $\cos (\phi - \theta)$.

Although it is preferred that the spreader 150 should be located roughly one-third of the way from the low impedance end towards the high impedance end of the transformer as previously explained, the location of this spreader is not critical. If the spacing ratio D/d of the transformer is as great as 6, the spreader 150 may be located as near to this low impedance end of the transformer as one-seventh of the total transformer length and still the transformer will give good results. If the transformer spacing ratio is as low as 2, on the other hand, the spreader 150 may be located as much as two-thirds of the transformer length from the low impedance end of the transformer. Thus the above mentioned rule that the spreader should be located at a distance from the low impedance end which is of the order of one-third of the total transformer length, can only be considered as an approximate rule applicable to transformers which have spacing ratios of the magnitude most commonly used.

For any given transformer spacing ratio the optimum position for the spreader 150 can be approximately determined from an inspection of the spacing curve of the transformer conductors without a spreader. Referring to Fig. 10, for example, which graphically represents the variation of conductor spacing along the transformer length for a transformer having a spacing ratio of 6 and for another transformer having a spacing ratio of 2, it will be observed that for the transformer with a spacing ratio of 2, the conductor distance becomes less than d at a point which is .4 times the transformer length from the low impedance terminal. Therefore, if the ideal desired curve of conductor spacing must not at any point become less than the low impedance distance d , it is clear that the spreader should be set more than .4 times the transformer length from the low impedance terminals in the case of a transformer having a spacing ratio of 2. For such a transformer, a satisfactory value of A would be approximately .5 to .8 times the total transformer length. On the other hand, for a transformer whose spacing ratio D/d was equal to 6, a much smaller value of A would clearly be suitable. As can be seen from the upper curve of Fig. 10, the conductor separation for such a transformer does not fall below the value d until the plane of measurement is about .07 times the total transformer length from the low impedance terminal. For such a transformer, therefore, the distance A could be taken to be somewhere between .2 and .6 times the total transformer length. If a very accurate transformer design is desired, the optimum position of the spreader 150 can be still more accurately determined by first estimating the region for locating this spreader from curves such as shown in Fig. 10 in the manner above outlined, and then assuming two different spreader locations within this estimated region. The resulting curves of conductor spacing for the two assumed positions of the spreader may then be readily calculated from Formulae (2) and (4), and these two curves can then be compared with an ideal curve plotted from Formula (1). Ordinarily both of the assumed curves will be sufficiently closely similar to the ideal curve for all practical purposes, but by checking one or two assumed curves in the manner just outlined, it is

possible to obtain a still more accurate correspondence between the actual conductor spacing and the ideal conductor spacing.

It is, of course, apparent that more than one spreader might be employed in order to obtain a still more accurate correspondence between the actual and theoretical conductor spacing, although it is believed that in practice a single spacer is sufficient when the transformer is constructed in accordance with Figs. 5, 6, 7, 8 and 9. In any event the number of spacers required for simulating the theoretically desired curve with a given degree of approximation will always be considerably lessened by the twisting arrangement of the present invention.

While certain embodiments of my invention have been disclosed for the purpose of illustration, it will be understood that modifications, adaptations and variations thereof such as would occur to one skilled in the art may be made without departing from the scope of my invention as defined in the appended claims.

What I claim is:

1. A high frequency aperiodic transformer comprising a first pair of supports, a second pair of supports spaced from said first pair of supports and disposed in a different plane from that of said first pair and separated by a smaller distance than said first pair of supports, and two conductors of substantially uniform cross-section each stretched from one of said first pair of supports to one of said second pair of supports said supports being so related that said conductors are not in the same plane, whereby a non-linear spacing relationship exists between the conductors to effect the desired impedance transformation.

2. A high frequency aperiodic transformer comprising a first pair of supports, a second pair of supports disposed in a different plane arranged at an angle to the plane of said first pair and separated by a smaller distance than said first pair of supports, and two conductors of substantially uniform cross-section each extending substantially linearly from one of said first pair of supports to one of said second pair of supports

said conductors being in mutually exclusive planes, whereby a non-linear spacing relationship exists between said conductors.

3. A transformer arrangement in accordance with claim 2, wherein said two conductors are extended to a third pair of supports which lie in a different plane from that of said second pair of supports arranged at an angle to said first named different plane and separated by a still smaller distance than said second pair of supports, and conductors between said second and third supports arranged in mutually exclusive planes to form an additional transformer.

4. A high frequency aperiodic transformer comprising a first pair of supports lying in a first line, a second pair of supports spaced from said first pair of supports and lying in a second line which forms an angle with said first line, a first conductor stretched between one support of said first pair and one support of said second pair, a second conductor stretched between the other support of said first pair and the other support of said second pair, and a spacer fixing the mutual separation of said conductors intermediate said supports whereby said two conductors form two component transformers each consisting essentially of two straight conductors and joined end to end the conductors of each transformer lying in mutually exclusive planes whereby linear spacing relationship exists therebetween.

5. A transformer according to claim 4, wherein said angle is 90°.

6. A high frequency aperiodic transformer comprising a first pair of supports lying in a first line, a second pair of supports lying in a second line which forms an angle of 90° with said first line, a first conductor stretched between one support of said first pair and one support of said second pair, and a second conductor stretched between the other support of said first pair and the other support of said second pair whereby a non-linear spaced relationship exists between said conductors and the desired impedance transformation action is produced.

ANDREW ALFORD.
